UNITED STATES PATENT OFFICE.

HARRY SCHAEFFER, OF BROOKLYN, NEW YORK.

DESIGN FOR A BABY-CARRIAGE HOOD.

Application filed May 26, 1922. Serial No. 2,434. Term of patent 7 years.

To all whom it may concern:

Be it known that I, HARRY SCHAEFFER, a citizen of the United States of America, residing at Brooklyn, Kings County, State of New York, have invented a new, original, and ornamental Design for a Baby-Carriage Hood, of which the following is a specification, reference being had to the accompanying drawing, forming part hereof, in which Fig. 1 is a perspective view of a baby carriage hood having my new design, looking from the rear.

I claim;—

The ornamental design for a baby carriage hood, as shown.

Signed at New York city, N. Y., this 24 day of May, 1922.

HARRY SCHAEFFER.
